[57] CLAIM

The ornamental design for telephone stand, as shown and described.

DESCRIPTION

FIG. 1 is a top, front and left side perspective view of a telephone stand embodying our new design;

FIG. 2 is a top plan view thereof;

FIG. 3 is a bottom plan view thereof;

FIG. 4 is a side elevation thereof, the opposite side being essentially a mirror image of the side shown;

FIG. 5 is a front elevation view thereof; and

FIG. 6 is a rear elevation view thereof.

FIG. 1

FIG. 2

FIG. 3

FIG. 4

FIG. 5

FIG. 6
